UNITED STATES PATENT OFFICE.

JAMES KRONDAK, OF MORSE BLUFF, NEBRASKA.

DRAFT EVENER.

Application filed April 8, 1927. Serial No. 182,039.

This invention relates to improvements in draft equalizers and more particularly to a device of this character adapted for use by three or more draft animals, although it is capable of other uses. One object is to provide a draft equalizer that is positive and efficient in operation and that can be readily applied to vehicle tongues of ordinary construction.

With the foregoing and other objects in view the invention consists in the combination and arrangement of parts to be herein-after fully described, particularly pointed out in the claims and illustrated in the accompanying drawings which form a part of this application and in which—

Fig. 1 is a top plan view of the draft equalizer applied to a vehicle tongue.

Fig. 2 is a view of Fig. 1 in rear elevation.

Figs. 3 and 4 are enlarged cross sectional views taken, respectively, on lines 3—3 and 4—4 of Fig. 1.

Fig. 5 is a longitudinal sectional view through the main bar of the invention and is taken on line 5—5 of Fig. 1.

Like reference characters denote corresponding parts throughout the several views.

Where the power or pull is unequally divided upon the sides of the vehicle pole it is the purpose of the present invention to equalize the draft. This is accomplished by the novel arrangement and assembly of means for receiving and distributing the stress on the several members associated with the pole and comprising a splinter bar that extends across the pole and is connected thereto by mechanism arranged upon each side of and across the pole.

The reference numeral 1 denotes the vehicle pole of common formation. A bolt 2 extending through the vehicle pole secures thereto one end of the hammer strap 3, the body of said strap being raised relative to said pole and extending longitudinally thereof, the forward end thereof being spaced above the pole and supported upon the bushing 4 of a bolt 5 that likewise extends through the pole. Secured to the hammer strap 3 by a bolt 6 is one end of an angular or L-shaped lever 7 that extends out laterally from said strap and is further secured thereto and to the pole by the brace strap 8. The outer and shorter end of the lever 7 is pivotally received in one bifurcated end of an angle bar 9 and secured therein by bolt 10.

The angle bar 9 extends inwardly from

the shorter end of the lever 7 across the pole 1 and beneath the forward end of the hammer strap 3 and is fulcrumed upon a bolt 11 that connects it to the splinter bar 12, the shorter end of said bar 9 being connected by bolt 13 to the straight bar 14 that extends inwardly to the pole 1 and is connected by bolt 15 to the triangular plates 16, 17 that engage with the horizontal faces of the bar 14 and connect said bar to the splinter bar 12 to which said plates are secured by the bolt 18, a brace strap 19 extending longitudinally of the pole 1 but spaced thereabove also connecting the bolts 18 and 15.

Connecting the apex of each triangular plate 16, 17 by means of bolt 20 are the parallel spaced straps 21, 22 that are also connected by bolt 23 to one end of the right angled lever 24 that is fulcrumed upon a bolt 25 to which a pair of parallel spacer straps 26, 27 are secured that are also connected by bolt 11 to the splinter bar. Likewise secured to the bolt 25 are the spacer straps 28, 29 also connected by bolts 30 to the splinter bar, the straps 28, 29 taken with straps 26, 27 and splinter bar 12 forming a triangle to the apex of which the lever 24 is fulcrumed.

Referring again to the lever 24 a bolt 31 passing through the end thereof remote from bolt 23 engages the bifurcated end of the take-up bar 32 the opposite end of which is threaded and adjustably connected to the yoke 33 that is connected by bolt 34 to the lever 7, said take-up bar and yoke extending from one side of the tongue 1 to the other. A doubletree (not shown) is secured to the shorter end of the splinter bar and a single-tree (not shown) to the longer end.

The forward pull of the draft animals upon the splinter bar would be transmitted from the through bolts 18, 11, 30. A straight line connecting the bolts 25, 11 would pass through the bolt 31 and pass to the right of the bolt 13. Should the pull of the draft animals at the doubletree on the shorter or right end of the splinter bar be excessive this pull would be equalized by the strain passing from bolt 18 through bolt 15, then to the left of the pole through straight bar 14 and it would be applied to angle bar 9 to the left of its fulcrum point 11 thereby tending to bring forward the longer side of this bar, upon the right side of the pole, thus pulling forward upon the lever 7 to which the yoke 33 is pivoted at 34. Through yoke 33 and take-up bar 32 the strain would be

transmitted to lever 24 through bolt 31 thus 5
tilting this lever upon its fulcrum 25 and
bringing forward bolt 23 and straps 21, 22
which would transmit through bolt 20 to
plates 16, 17 to bolt 15. In the present
construction and assembly the splinter bar
is so disposed relative to the pole 1 that one
third of the length of the splinter bar is
normally upon the right hand side of the
pole 1 and two thirds of the splinter bar
upon the left side thereof. Should the pull
of the draft animals cause a slide draft
which would move the splinter bar to the
left relatively to the pole it would be the
purpose of the equalizing mechanism to auto-
matically re-position these members.

In the present relative positions of the
splinter bar and pole a straight line con-
necting the bolts 34, 10 should be more than
20 twice the distance from the pole of a
straight line connecting the bolts 25, 31.
This will cause any pull that would exert
a side draft to the left to correct itself as
the leverage exerted through the angle bar
9 and members 32, 33 moving forward
25 upon the right side of the tongue would
cause sufficient pressure upon the splinter bar
through bolt 11 and connections and upon
straight bar 14 and straps 21, 22 to plates 16,
30 17 to position bolts 18, 15 in a straight line
parallel with the tongue and in this position
of the bolts 18, 15 relative to the tongue the
relative positions of the splinter bar and
tongue must be correct. The adjustment
35 between the yoke 33 and take-up bar 32
permits proper adjustment of the several
connected elements of the device.

What is claimed is:—

1. In a draft equalizer, a splinter bar
40 extending transversely of the vehicle draft
pole, an angle bar pivotally connected to
the splinter bar upon one side of the pole

and extending from said pivotal point to
both sides of said splinter bar and of the
pole, an L-shaped bar pivotally connecting 45
one end of said angle bar and the pole
upon the side thereof remote from the
pivotal point of said angle bar, spacer straps
connected to the splinter bar, a right angled
lever fulcrum to said spacer straps, adjust- 50
able yoke and take-up connection between
one end of said right angled lever and
L-shaped bar, spaced triangular plates
pivotally secured to said splinter bar, straps
connecting said triangular plates and right 55
angled lever, and connection between the said
angular bar and said triangular plates.

2. In a draft equalizer, a splinter bar
extending transversely of the vehicle draft
pole, an angle bar pivotally connected to 60
the splinter bar upon one side of the pole
and extending from said pivotal point to
opposite sides of the splinter bar and of the
pole, an L-shaped bar pivotally connecting
one end of said angle bar and the pole upon 65
the side thereof remote from the pivotal
point of said angle bar, spacer straps con-
nected to the splinter bar upon the side of
the pole opposite to said L-shaped bar, a
right angled lever fulcrum to said spacer 70
straps, adjustable yoke and take-up connec-
tion between one end of said right angled
lever and L-shaped bar and extending across
the pole, spaced triangular plates pivotally
secured to said splinter bar, straps connect- 75
ing said triangular plates and right angled
lever and disposed wholly upon the side of
the pole opposite to said L-shaped lever, and
connection between said angular bar and
triangular plates upon the same side of said 80
pole as said last named straps.

In testimony that I claim the foregoing as
my own I have hereto affixed my signature.

JAMES KRONDAK.
